PERFORATING MACHINE

Henry Ruppert, Woodside, N. Y., assignor to
Leedall Products, Inc., New York, N. Y., a cor-
poration of New York

Application March 11, 1939, Serial No. 261,166

11 Claims. (Cl. 164—89.5)

The invention relates to machines for perforating sheet material; for instance, in the formation of a plurality of apertures in any of variegated designs to stencil patterns used in the manufacture of clothing or any materials which are superimposed in different thicknesses constituting a plurality of layers in which designs for decorative purposes, secured by punching apertures in the material, are imparted by means of a master pattern. The perforating machine of the present invention is equally applicable to the punching of apertures in one or more layers of material, whether a fabric, paper or leather.

One of the objects of the invention is to provide a perforating machine of this general type which is completely mobile, so as to make it possible to move the entire machine over an expansive surface or area in any direction so as to apply the perforations in any design, including those involving a curved alignment and abrupt changes in the direction of the line of perforations. Any of many complicated forms and therefore decorative designs are thus possible of application with my mobile type of perforating machine, which does not, as do certain structures of the prior art, embody a rigid frame associated with a stationary work support and which are characterized by the disadvantage that only straight lines of perforations are capable of application to the material treated.

A further object of the invention is to provide a perforating machine embodying a hammer operative upon the punch, which in turn is mechanically lifted by the hammer, as distinguished from prior art structures in which the punching element is released or withdrawn from the material operated upon by a spring.

A still further object of the invention is to provide a perforating machine embodying an adjustable mechanism for regulating the pressure of the hammer, so that the perforating machine may be applied to produce perforations in different thicknesses of material of different constitution and character.

A still further object of the invention is to provide such a perforating machine with a trigger type of control keeping the punch operating hammer in upright position.

A still further object of the invention is to provide upon the perforating machine a recessed base plate of such form and contouration as to make possible in conjunction with the mobility of the apparatus as a whole the application of a variety of designs of different form to the material operated upon.

A specific embodiment of my novel perforating machine is illustrated in the accompanying drawings, in which Fig. 1 is a vertical partially sectional view through the machine, along the lines 1—1 of Fig. 2; Fig. 2 is a plan view of the machine; Fig. 3 is a vertical section along the line 3—3 of Fig. 2; and Fig. 4 is a section along the line 4—4 of Fig. 2.

Referring more particularly to the drawings, in which similar reference characters identify similar parts in the several views, my novel perforating machine comprises a gripping handle of a configuration facilitating its grasping by one hand of the operator. The handle 5 is supported upon a base 6 of substantially oval form having a recess 7 in the forward portion thereof.

Supported upon the upper edge of the handle 5 is a plate 8 through an aperture of which near the handle 5 is mounted a switch 9, the operating handle 10 of which is thus positioned so as to be within easy reach of the thumb of the operator while the machine is being grasped by the hand, with the palm encompassing the handle 5 and the fingers in operative contact straddling the trigger 11. The trigger 11 is pivoted upon a screw 12 passing through an upstanding projection 13 of a vertically disposed block 14, which acts as one of the bearings for a shaft 15 upon which the fulcrum member 16 of the hammer is mounted. The opposite end of the shaft 15 is supported within a block extending from the plate 8.

Supported upon the plate 8 is an electric motor 18, to the end of the shaft to which is secured a pinion 19 meshing with a gear 20 supported upon a shaft 21 within bearings 22, 23, extending upwardly from the plate 8. Operatively secured to the gear 20, and upon the shaft 21 is a cam 24, the high dwell 25 of which, upon rotation of the cam is adapted to press downwardly upon the rearwardly extending portion of the hammer to cause the hammer to be rotated about its fulcrum 16, the body of the hammer 27, extending forwardly of its fulcrum thus being raised, carrying with it the integral hammer head 28.

Secured to the hammer body 27 is a stop plate 29 having a heel portion 30 which, upon rotation of the hammer about its fulcrum, engages a recess 31 in the trigger, thereby acting as a stop, so that when the trigger 11 is released by the fingers of the operator, the hammer 27 ceases operating. In this manner, full control of the punching machine, even when the switch 9 is on and current supplied to the motor, is had by means of the trigger, the hammer operating to

cause the perforating in the material only during such times that the trigger is under pressure, and ceasing to operate immediately after pressure on such trigger is released, depending upon 5 the exact position of the hammer arm 30.

When the hammer has been raised by the mechanism and in the manner hereinabove described, it is caused to descend by means of its own weight and a spring 32 anchored at one end 10 to the projection 33 extending downwardly from the fulcrum of the hammer and at its other end to a pin 34 extending from a block 35 mounted for linear movement upon a threaded shaft 36 which may be rotated, for adjustment of the 15 tension of the spring 32, by a knob 37.

The electrical circuit to the motor includes a speed regulator generally designated at 38, which includes an ordinary rheostat 39 and a regulating knob 40.

20 Pivoted at the forward end of the block 14 is a lever 41 having a bifurcated end 42 straddling the shaft 43 of the punch between disc 44 and disc 45 at the upper end thereof. The element 41 at its rear end is engaged by the rear end of 25 element 29. Surrounding the shaft 43 is the hollow punch 46 having the perforating nose 47. The punchings may be disposed of in any convenient manner, for instance, upon removal of 30 punching 46 periodically from the hollow interior thereof. The punch is secured within a housing 48 preferably threaded into the plate 8 near the forward end thereof, with the punch extending downwardly immediately in advance of the opening of the recess 7 in the base plate 6 of the 35 apparatus.

Extending and supported from the plate 8 there may be provided a lamp housing 49 in which may be secured an incandescent lamp 50 for illuminating the surface of the material being 40 perforated. The electrical connections, including the circuit from the switch to the motor, the speed regulator and the lamp are not shown as they may be conventional.

The operation of my novel perforating machine is as follows:

45 The machine is grasped by the operator by the gripping handle 5, with the fingers of the same hand extending over the front portion of the trigger 11 and the thumb in substantial 50 proximity to the switch lever 10. The motor is then started by throwing the switch 9 by means of its controlling lever 10 and when the operation of perforating is to be begun, the trigger is 55 pressed inwardly with the fingers. This operation will release the stop and cause the rotation of the cam 24 to depress the heel portion of the hammer, thereby raising the head of such hammer. The spring 32 and the weight of the 60 hammer head will then cause the lowering of said head, lowering the punch 47 into the material. The next rotation of the cam 24 will then again cause the raising of the hammer at the same time pivoting the lever 41 to raise the punch and lift it out of the material to permit the proper 65 spacing of the apertures. This operation of the mechanism continues, the operator moving the entire machine over the surface of the material to be perforated, following any particular design to be imparted to such material by the line of 70 perforations to be made.

75 When the line of perforations is to be interrupted, for instance for the purpose of moving the machine to a different portion of the surface of the material, to again impart a new line of perforations thereto, the trigger 11 may be en-

gaged with 30 by releasing the pressure of the fingers thereon, the hammer being then automatically interrupted in its operation by the stop mechanism. Upon again exerting pressure upon the trigger, the hammer may again be 5 brought into operation.

The speed regulator 38 may be adjusted in well known fashion to cause a variance in the speed with which the hammer is raised and released. Depending upon the nature and thickness of the material operated upon, the operation of the hammer may be controlled by the tension imparted to the spring 32 by turning of the knob 37 to cause the block 35, to the pin 34 of which the spring is anchored, to move along 15 the threaded shaft 36.

While I have described and illustrated a specific embodiment of my invention, it is obvious that various changes therein, particularly in the arrangement and configuration of the several 20 parts thereof, may be made without departing from my invention.

I claim:

1. A perforating machine of the type described comprising a mobile base plate slidable manually 25 over the material to be perforated, a gripping handle extending upwardly therefrom, a plate supported on said handle, a fulcrumed hammer mounted upon said plate, means for raising the forward end of said hammer by depressing the 30 end thereof extending rearwardly of its fulcrum, a spring for lowering the forward portion of said hammer, and a perforating tool positioned for reciprocating movement beneath the hammer, said fulcrumed hammer having a separate move- 35 ment from said perforating tool.

2. A perforating machine of the type described comprising a mobile base plate slidable manually over the material to be perforated, a gripping handle extending upwardly therefrom, a plate 40 supported on said handle, a fulcrumed hammer mounted upon said plate, means for raising the forward end of said hammer by depressing the end thereof extending rearwardly of its fulcrum, a spring for lowering the forward portion of said 45 hammer, and a perforating tool positioned for reciprocating movement beneath the hammer, said fulcrumed hammer having a separate movement from said perforating tool and means for interrupting the operation of said hammer. 50

3. A perforating machine of the type described comprising a mobile base plate slidable manually over the material to be perforated, a gripping handle extending upwardly therefrom, a plate supported on said handle, a fulcrumed hammer 55 mounted upon said plate, means for raising the forward end of said hammer by depressing the end thereof extending rearwardly of its fulcrum, a spring for lowering the forward portion of said hammer, a perforating tool positioned for reciprocating movement beneath the hammer said fulcrumed hammer having a separate movement from said perforating tool, and means for adjusting the tension of said spring. 60

4. A perforating machine of the type described 65 comprising a mobile base plate slidable manually over the material to be perforated, a gripping handle extending upwardly therefrom, a plate supported on said handle, a fulcrumed hammer mounted upon said plate, means for raising the 70 forward end of said hammer by depressing the end thereof extending rearwardly of its fulcrum, a spring for lowering the forward portion of said hammer, a perforating tool positioned for reciprocating movement beneath the hammer, means 75

for adjusting the tension of said spring, and means for interrupting the operation of said hammer.

5. A perforating machine of the type described comprising a mobile base plate slideable manually over the material to be perforated, a gripping handle extending upwardly therefrom, a trigger extending along said handle, a plate supported on said handle, a pivoted hammer mounted upon said plate, means for raising the forward end of said hammer by depressing the end thereof of extending rearwardly of its fulcrum, an adjustable spring for lowering the forward portion of said hammer, and a perforating tool positioned 10 for reciprocating movement beneath the hammer said fulcrumed hammer having a separate movement from said perforating tool, and said trigger being effective for interrupting the operation of said hammer.
- 10 6. A perforating machine of the type described comprising a mobile base plate slideable manually over the material to be perforated, a gripping handle extending upwardly therefrom, a trigger extending along said handle, a plate supported 15 on said handle, a pivoted hammer mounted upon said plate, means for raising the forward end of said hammer by depressing the end thereof of extending rearwardly of its fulcrum, an adjustable spring for lowering the forward portion 20 of said hammer, a perforating tool positioned for reciprocating movement beneath the hammer, and means for interrupting the operation of said hammer, said means comprising a stop plate extending rearwardly of the hammer and 25 having a portion engaging the trigger whereby when the trigger is released, the hammer will be in a position of rest.
7. A perforating machine of the type described comprising a mobile base plate slideable manually over the material to be perforated, a gripping handle extending from said base plate, a supporting plate disposed horizontally upon said gripping handle, an electric motor mounted upon said plate, a fulcrumed hammer having a head 30 and a rearwardly extending projection, a cam rotated by means of said motor to fulcrum the hammer, a spring secured to the hammer to cause a lowering of the head thereof, a trigger mechanism for the fulcrumed hammer, secured to, and so as to partially enter, said gripping handle, and a perforating tool depending from 35 said supporting plate to in front of said base plate, said fulcrumed hammer having a separate movement from said perforating tool and means for adjusting the tension of said spring for regulating the pressure of the hammer.
- 40 8. A perforating machine of the type described comprising a mobile base plate slideable manually over the material to be perforated, a gripping handle extending from said base plate, a supporting plate disposed horizontally upon said gripping handle, an electric motor mounted upon said plate, a fulcrumed hammer having a head 45 and a rearwardly extending projection, a cam rotated by means of said motor to fulcrum the hammer, a spring secured to the hammer to cause a lowering of the head thereof, a trigger mechanism for the fulcrumed hammer, secured to, and so as to partially enter, said gripping handle, and a perforating tool depending from said supporting plate to in front of said base plate, said fulcrumed hammer having a separate movement 50 from said perforating tool and means for adjusting the tension of said spring for regulating the pressure of the hammer.
- 45 9. A perforating machine of the type described comprising a mobile base plate slideable manually over the material to be perforated, a gripping handle extending from said base plate, a supporting plate disposed horizontally upon said gripping handle, an electric motor mounted upon said plate, a fulcrumed hammer having a head 55 and a rearwardly extending projection, a cam rotated by means of said motor to fulcrum the hammer, a spring secured to the hammer to cause a lowering of the head thereof, a stop plate upon one side of the hammer and having a rearwardly projecting nose, a trigger mechanism secured to, and so as to partially enter said gripping handle and having a recess near the upper edge thereof within which the projecting nose of said stop plate is adapted to enter to prevent the hammer from operating a perforating tool depending from said supporting plate to in front of said base plate, and a pivoted lever having a bifurcated end for lifting the tool out of the material for the spacing of apertures therein, said lever being pivoted by the nose projecting rearwardly from the stop plate, said perforating tool having a pair of horizontally disposed discs near the upper extremity thereof, the portion of the tool between said discs being straddled by the bifurcated 60 end of said pivoted lever.
- 50 10. A perforating machine of the type described comprising a mobile base plate slideable manually over the material to be perforated, a gripping handle extending from said base plate, a supporting plate disposed horizontally upon said gripping handle, an electric motor mounted upon said plate, a fulcrumed hammer having a head 65 and a rearwardly extending projection, a cam rotated by means of said motor to fulcrum the hammer, a spring secured to the hammer to cause a lowering of the head thereof, a stop plate upon one side of the hammer and having a rearwardly projecting nose, a trigger mechanism secured to, and so as to partially enter said gripping handle, and a perforating tool depending from said supporting plate to in front of said base plate, said fulcrumed hammer having a separate movement 70 from said perforating tool and means for adjusting the tension of said spring for regulating the pressure of the hammer.

HENRY RUPPERT.
